UNITED STATES PATENT OFFICE

2,026,266

DISPENSING HOLDER

Philip C. P. Booty, Chicago, Ill.

Application January 9, 1930, Serial No. 419,515

3 Claims. (Cl. 206—56)

My invention relates to dispensing holders for sticks of nail polish or the like, and it is the object of my invention to provide a new and improved form of container for such sticks which shall serve to protect the sticks effectively for shipment or for being carried in the ordinary bag or vanity case even when such sticks are made up in extremely fragile form, and which will protect the body of the stick while a quantity of the polish or similar product is being rubbed from the end of the stick for use. By the provision of an effective dispensing holder of this type, I am enabled to make use of a stick of polish or other powder prepared by pressure 10 into an agglomerate mass without the use of any binder of any sort. Since the use of binders is highly objectionable in products of this type, it will be seen that the provision of a suitable holder for the fragile stick of this type is correspondingly important.

It is one of the objects of my invention to provide a device of this type of simple form, the parts of which can be produced readily and cheaply, and which can be expeditiously and easily assembled. It is another object of my invention to provide easily controlled means for regulating the distance to which the stick of polish shall protrude for insuring both a satisfactory margin of safety against breakage of the stick and also the 30 desirable ease and convenience of use.

It is another object of my invention to improve devices of this type in sundry details hereinafter pointed out. The preferred means by which I have accomplished my several objects 35 are illustrated in the drawing. That which I believe to be new and desire to cover by Letters Patent is set forth in the claims.

In the drawing,—

Fig. 1 is a perspective view of my improved 40 device;

Fig. 2 is a central vertical section through my device shown on an enlarged scale and partially broken away;

Fig. 3 is a vertical sectional view of the rear 45 end portion of my improved device showing the position of the parts when the stick is being pushed forwardly in the container;

Fig. 4 is a side view of the end portion of the device with the cap removed ready for use of the 50 stick;

Fig. 5 is a vertical sectional view of the forward end portion of the device with the stick pushed forwardly to the limit of its movement at substantially the end of the usefulness of the 55 device; and

Fig. 6 is a central vertical sectional view of the forward end of a device of slightly modified construction.

Referring now to Figs. 1 to 5 inclusive, in which corresponding parts are indicated by the same reference characters, 10 indicates a sleeve formed of paper, metal or any other appropriate material, having a head slidably mounted therein. In the construction shown, the head comprises a block 11 of wood or other suitable material having a working fit within a short sleeve 12 which in turn has a working fit in the sleeve 10, the sleeve 12 in the construction shown being formed of paper. Upon the rear face of the block 11, I have provided a disc 13 of felt or similar stiff yielding material, such disc being secured by means of adhesive to the rear face of the block 11 but being free from the sleeve 12. By reason of this arrangement, when pressure is applied to the rear face of the disc 13, the head is readily given a sliding movement toward the right, as shown in Fig. 3, the outer edge portion of the disc 13 being free to yield backwardly with respect to the sleeve 12 so as to permit such movement with only slight frictional resistance with 20 respect to such movement. When, however, pressure is applied upon the front face of the head, the entire edge portion of the disc 13 stands in contact with the inner face of the sleeve 10, and provides a very strong resistance with respect to 25 movement of the head backwardly through the sleeve 10.

As is clearly shown in the drawing, the short sleeve 12 extends forwardly a short distance beyond the forward face of the block 11, serving 35 thus to provide a socket for the reception of the rear end of a cosmetic member 14 in the form of a stick, the stick 14 having a working fit in said socket. In the construction shown, the stick 14 40 comprises nail polish in the form of a powder given its stick form by heavy pressure applied to the material, the polish being pressed into its stick formation without the use of any binder therefor. Such stick is of very fragile form so as to require effective protection for handling. 45 For providing the desired protection, I have provided a cork collar 15 at the forward end of the sleeve 10, such collar 15 being preferably secured in position in the sleeve 10 by means of adhesive. 50 By the provision of the cork collar 15 and the end portion of the sleeve 12 serving to space the stick 14 from the wall of the sleeve 10, I have provided a cushion mounting for the stick such as to enable the device as a whole to stand up 55

under normal conditions of use without undue danger of being crushed.

Upon the rear end of the sleeve 10, I have provided a reenforcing ring 16 preferably of metal serving to strengthen the rear end of the sleeve 10.

Upon the forward end of the sleeve 10, I have provided a cap 17 formed of sheet metal and having a working fit on the end of the sleeve 10.

Upon the inner face of the end wall of the cap, I have provided a cork sleeve 18 which serves to space the end wall of the cap from the end of the sleeve 10, the size of the collar 18 being such as to bring the end wall of the cap into the desired spaced relation beyond the end of the sleeve 10 so as to act as a stop for limiting the forward movement of the stick 14 within the sleeve 10. When it is desired to feed the stick 14 forwardly for use, the cap 17 is to be placed in position and pressed firmly against the sleeve 10, whereupon the stick 14 is moved forwardly into contact with the cap. The extent to which the stick protrudes beyond the end of the sleeve 10 is thus controlled so as to afford ready and convenient use of the stick while at the same time affording the necessary protection and reinforcement to the stick.

In Fig. 6 I have shown a modified construction in which a cap 19 is provided without the use of a collar such as the collar 18 of the construction shown in Fig. 2. The arrangement in Fig. 6 is such that the end wall of the cap 19 stands in the desired spaced relation with respect to the end of the sleeve 10 when the cap is pressed to its normal effective closing position.

While I prefer to employ the construction as shown in the drawing, it is to be understood that I do not limit my invention to such construction except so far as the claims may be so limited by the prior art.

I claim:

1. A device of the type described, comprising

in combination a sleeve, a cosmetic in the form of a stick, a cork collar secured in one end of said sleeve in which said stick has a frictional bearing and by which the stick is held yieldingly in spaced relation to the wall of the sleeve, and a head slidably mounted in said sleeve adapted to support the rear end of said stick in spaced relation to the wall of the sleeve.

2. A device of the type described, comprising in combination a sleeve, a cosmetic in the form of a stick, means at one end of said sleeve for holding said stick in spaced relation to the wall of the sleeve and serving as a frictional mounting for said stick, a block slidably mounted in said sleeve opposite the end of said stick of cosmetic, and a thick heavy retaining member of felt fixedly secured to the rear face of said block with an edge portion engaging the wall of the sleeve and yieldable backwardly with respect to the block so as to permit free movement of the block forwardly but normally preventing backward movement of the block in the sleeve.

3. A device of the type described, comprising in combination a sleeve, a cosmetic in the form of a stick, means at one end of said sleeve for holding said stick in spaced relation to the wall of the sleeve and serving as a frictional mounting for said stick, and a head slidably mounted in said sleeve for supporting said stick in operative position in the sleeve and comprising a shorter sleeve having a working fit in said first named sleeve, a block having a working fit in the rear end portion of said second sleeve, and a disc of felt fixedly secured to said block with its edge portions in frictional engagement with said first named sleeve and free to yield backwardly with respect to said second sleeve serving to permit free movement of said second sleeve and said block forwardly for advancing the stick but normally preventing backward movement of said second sleeve in said first named sleeve.

PHILIP C. P. BOOTY.
